UNITED STATES PATENT OFFICE

144,969

DESIGN FOR A LINOLEUM OR SIMILAR HARD-SURFACED RUG

Robert V. Garner, Westwood, and Angelo P. Macchi, Walpole, Mass., assignors to Bird & Son, Inc., East Walpole, Mass., a corporation of Massachusetts

Application September 21, 1945, Serial No. 122,242

Term of patent 7 years

(Cl. D92—21)

To all whom it may concern:

Be it known that we, Robert V. Garner and Angelo P. Macchi, citizens of the United States, residing, respectively, at Westwood and Walpole, in the county of Norfolk and Commonwealth of Massachusetts, have invented a new, original, and ornamental Design for a Linoleum or Similar Hard-Surfaced Rug, of which the following is a specification, reference being had to the accompanying drawing, forming a part thereof.

The figure of the drawing is a plan view of corner portion of a linoleum or similar hard-surfaced rug showing our new design. The design repeats to the bottom and left of the figure to any desired extent except as to the remaining corners which repeat the corner design shown.

We claim:

The ornamental design for a linoleum or similar hard-surfaced rug, as shown and described.

ROBERT V. GARNER.
ANGELO P. MACCHI.
